Inventor:
Halbert B. Hallorsen
by

UNITED STATES PATENT OFFICE.

HALBERT B. HALVORSEN, OF CHICAGO, ILLINOIS, ASSIGNOR TO SULLIVAN MACHINERY COMPANY, A CORPORATION OF MASSACHUSETTS.

DISPLACEMENT PUMP.

Application filed August 11, 1921. Serial No. 491,508.

My invention relates to displacement pumps.

An object of my invention is to provide an improved displacement type pump. Another object of my invention is to provide an improved displacement type pump having improved automatically controlled means for the supply of the pumping medium thereto. A further object of my invention is to provide an improved displacement type pump in which the control may be accomplished without the reliance upon floats and by the weight of the liquid being pumped. Other objects of my invention will herein after more fully appear.

In the accompanying drawings I have shown for purposes of illustration one form which my invention may assume in practice.

20 In these drawings,—

Fig. 1 is a side elevation of the illustrative form of my improved pumping mechanism, parts being shown in section.

25 Fig. 2 is a plan view of the mechanism shown in Fig. 1.

Fig. 3 is an end view, the view being taken from the right hand end of Fig. 1.

Fig. 4 is a central vertical section on the line 4—4 of Fig. 1.

30 Figs. 5 and 6 are details of the valve mechanism.

My improved pumping mechanism comprises a pair of displacement tanks 1 and 2 rigidly mounted upon a beam 3 which is 35 in turn pivotally mounted as best shown in Fig. 4 upon a base member 4 which is provided with upstanding brackets 5 pivotally supporting said beam 3, the latter being in turn provided with depending hangers 6 for 40 supporting the same upon the transverse shaft 7 which is rotatably mounted in the brackets 5 in suitable anti-friction bearings. In the bottoms of each of the tanks 1 and 2 there are provided common inlet and discharge 45 connections 9 and 10 respectively, these connections communicating with transversely extending pipes 11 and 12 secured to the connections 9 and 10 beneath the beam 3. The transverse connections 11 and 12 50 communicate at opposite sides of the beam 3 with inlet and discharge connections 13 and 14 respectively, there being provided check valves 15 and 16 permitting flow only

toward the tanks in the connections between the line 13 and the pipes 11 and 12, and 17 55 and 18 permitting discharge only between the line 14 and the pipes 11 and 12. It will be evident from an inspection of Fig. 4 that the pipes 11 and 12 communicate beyond the check valves with X's 19 and 20, the adjacent sides of the latter being blanked off and the remote sides being provided with tubular sections 21 and 22 surrounded by suitable glands 23 and 24 whereby a movable but fluid tight connection may be arranged between the inlet and discharge lines 13 and 14 and the tanks 1 and 2.

It will be noted that the beam 3 carries at one end thereof a depending vertically disposed rack 25 adapted to cooperate with a spur gear 26 mounted upon a horizontal shaft 27 journaled as at 28 upon the end of the base 4 and that this shaft carries a suitably keyed, or otherwise held with respect thereto, arm 29 having a relatively heavy weight 30 thereon, the weight 30 being so proportioned relative to its leverage as to tend to counterbalance the weight of either of the tanks as they fill while the other is emptying. Suitable limit or stop means 31 80 and 32 are provided upon the base 4 to prevent excessive tipping of the beam 3.

For the purpose of supplying and exhausting air or other suitable pumping media to the tanks 1 and 2 whereby to cause the 85 discharge of the liquid from the tanks in alternation and to permit their re-filling, I support upon an arm 35 projecting upward from the end of the beam opposite the mechanism including the weight 30, a valve chest 36 in which a valve 37 is reciprocable, the valve 37 having a stem 38 sliding through a suitable gland 39 in the valve chest 36 and provided with stops 40 and 41 adapted to cooperate with the stationary abutment 90 member 42 secured to the frame 4, there being springs 43 and 44 surrounding the stem 38 between the abutment 42 and the stops 40 and 41 to cushion the action. It will thus be evident that as the beam tilts clockwise, the valve will, at approximately the end of the tilting movement, assume a position near the top of the casing, as its downward movement will be interrupted by engagement of the spring between the collar 40 and the abutment 42 with said parts 100 105

and so the casing 36 will move relatively to the valve. It will also be evident that a similar, but opposite, result will be accomplished upon the tilting of the beam in a counter-clockwise direction, the valve then being forced to assume a position toward the lower end of the casing.

Within the valve chest are a series of ports designated respectively 51, 52, 53, and 54, these ports opening through the surface of the valve chest over which the valve 37 moves. The port 51 is connected with the live pressure line 55. The port 52 connects with the line 56 leading to the top of the tank 1. Port 54 communicates with the line 57 leading to the top of tank 2 and port 53 leads to exhaust. It will be noted that the valve 37 is of a type in which a port 58 extends between and opens through the surfaces of the ends of the D, being similar in construction to the well-known Allen valve which is familiar in steam engine use. It will be noted that the valve 37 and the port 58 are so constructed that the tanks may be connected together when the valve is in substantially mid-position and prior to the connection of the tank, which has been receiving live air, with exhaust whereby a considerable quantity of air may be by-passed from one tank to the other and economy will be obtained.

The mode of operation of this mechanism will be readily apparent from the description so far given. Assume that the parts are in the position shown with air cut off from both of the tanks, the valve stem 38 will then be moved by hand to one of its extreme positions whereby to supply air under pressure to one of the tanks and connect the other with exhaust. In order to prevent the waste of the fluid being supplied to the tank connected with air, one or the other of the manually controlled stop valves 60 and 61 in the lines 56 and 57, respectively, will be closed. The tank in which atmospheric pressure alone exists will accordingly begin to fill by reason of the admission through the check valve 15 or 16 of liquid which flows in by gravity. As the liquid rises in the tank which is being filled, the weight 30 will be swung in one direction or the other, it being noted that the force necessary to move the weight increases as the weight moves more nearly toward a horizontal position. Approximately at the moment when the weight has reached horizontal position, the tank will become filled and as the arm reaches and crosses its horizontal position, its resistance will decrease and so a relatively rapid tilting movement of the beam will cause the valve chest to move to such an extent as to cause it to move relative to the valve, whose path is limited as described, in such manner as to shift relatively to the valve first to mid-position and

then to reverse position. As this occurs, the valve 60 or 61 which was closed may be opened as there will no longer be any discharge of waste air. The air admitted to the tank which had previously been filling will begin to discharge the liquid therefrom and the other tank will begin to fill under the gravity head of the liquid, the weight assisting the parts to return to initial position at such time as the tanks are equally filled. The discharge of liquid from the tank first filled will continue while the filling of the other will simultaneously go on until the tank first filled is emptied and the other full. The relative positions of the valve chest 36 and the valve 37 will then be reversed as previously described and the original operation continued, the sole difference being that the tank last filled will be discharged. The system now being in full operation will continue to operate automatically as long as liquid is supplied to it and pressure fluid is available to cause the discharge of the liquid from the tanks alternately. It will be evident that tilting movement of the beam 3 will be limited to the proper amount by the stops 31 or 32.

While I have in this application specifically described one embodiment which my invention may assume in practice, it will be understood that this form of the same is shown for purposes of illustration and that the invention may be modified and embodied in various other forms without departing from the spirit or the scope of the appended claims.

What I claim as new and desire to secure by Letters Patent is:

1. In a pump, a fluid container, tilttable fluid pressure means for pumping fluid therefrom, means for controlling said latter means comprising a valve, and an oscillatory weighted arm constantly cooperating therewith and adapted to operatively control said valve.

2. In a pump, a plurality of fluid containers, fluid pressure means for pumping fluid therefrom, means for controlling said latter means comprising a valve, an oscillatory weighted arm constantly cooperating therewith and operatively controlling said valve, and means for actuating said arm to vary the resisting force thereof.

3. In a pump, a fluid container, fluid pressure means for pumping fluid therefrom, means for controlling said latter means comprising a valve, an oscillatory weighted arm operatively controlling said valve, and means for actuating said arm to vary the resisting force thereof, said valve being adapted to be actuated after said force reaches its maximum.

4. In a displacement pump, a plurality of pivotally supported pumping tanks, counterbalancing means therefor, and means

- controlled by the tilting movement of said tanks to effect the admission and discharge of liquid with respect thereto.
5. In a displacement pump, a plurality of pivotally supported pumping tanks, counterbalancing means therefor, and means controlled by the tilting movement of said tanks for controlling the admission and exhausting of a pumping medium with respect thereto.
6. In a displacement pump, a plurality of pumping tanks, supporting means for said tanks, a pivotal mounting for said supporting means disposed between said tanks, counterbalancing means cooperating with said supporting means to retard the tilting of said tanks as the latter are emptied and filled, and means controlled by the tilting movement of said supporting means for controlling the supply and discharge of pumping fluid to and from said tanks.
7. In a displacement pump, a plurality of spaced pumping tanks, a support for said tanks, a pivotal mounting for said support, counterbalancing means controlled by said support for counterbalancing the weight of liquid admitted to said tanks, means for admitting and discharging liquid through the bottoms of said tanks, and means for alternately admitting and discharging pumping fluid through the tops of said tanks.
8. In a displacement pump, a plurality of tanks, means whereby liquid may be supplied to said tanks in alternation, and pressure fluid means for discharging said liquid comprising means controlled by the fluid being pumped operative to interconnect said tanks prior to the connection of the tank to which pressure had been supplied with a discharge line.
9. In a displacement pump, a plurality of movable tanks, means for supplying liquid to said tanks in alternation, and pressure fluid means for discharging said liquid comprising means made operative by movement of said tanks to interconnect said tanks prior to the connection of the tank to which pressure has been supplied with a discharge line.
10. In a displacement pump, a plurality of pivotally mounted tanks, and means comprising a relatively movable valve and valve chest for controlling the supply and exhaust of pumping fluid to and from said tanks, said members being tiltable with said tanks, one of said members being movable between given positions upon tilting thereof, and the other being movable over a shorter path limited by springs cooperating with a stationary abutment.
11. In a displacement pump, a plurality of pivotally mounted tanks, and means comprising a relatively movable valve and valve chest for controlling the supply and exhaust of pumping fluid to and from said tanks, said chest being tiltable with said tanks and
- movable between given positions upon tilting thereof, and said valve being movable over a shorter path limited by springs cooperating with a stationary abutment.
12. In a displacement pump, a tilting displacement tank, means controlled by the tilting of said tank for controlling the operation of said pump, and means operative to effect a retarded tilting movement during filling thereof and a more rapid movement when said tank is substantially full.
13. In a displacement pump, a plurality of displacement tanks, and means controlled by the weight of the liquid admitted to said tanks for controlling the supply of pressure fluid thereto for effecting the discharge of liquid therefrom and means for preventing operation of said control mechanism until one of said tanks is filled.
14. In a displacement pump, a plurality of pivotally mounted pumping tanks, and means for alternately filling and discharging said tanks comprising control mechanism controlled by the weight of a liquid admitted to said tanks and means cooperating with said tanks to prevent operation of said control mechanism until one of said tanks is filled.
15. In a displacement pump, a plurality of pivotally mounted pumping tanks having a fluid controlling valve associated therewith, means for alternately filling and discharging said tanks, and control mechanism therefor controlled by the tilting action including a swinging weighted arm.
16. In a displacement pump, a plurality of pivotally mounted pumping tanks, means for alternately filling and discharging said tanks controlled by the tilting movement thereof, and a pivoted weighted arm having an element cooperating with said tanks to control the tilting movement thereof.
17. In a displacement pump, a stationary base, a plurality of pivotally mounted pumping tanks thereon, means controlled by the tilting movement of said tanks to effect the admission and discharge of liquid with respect thereto, and means carried by said base and cooperating with said tanks to counterbalance the same.
18. In a displacement pump, a displacement tank, means controlled by the weight of the liquid admitted to said tank for controlling the supply of pressure thereto for effecting the discharge of liquid therefrom, and means including intermeshing elements to prevent preadmission of pressure prior to the discharge of liquid from said tank.
19. In a displacement pump, a stationary base, a plurality of pivotally mounted tanks thereon, means controlled by the tilting movement of said tanks to effect the admission and discharge of liquid with respect thereto, and means carried by said base comprising a weighted arm provided with a pin-

- ion, and a rack operatively connected to said tanks cooperating with said pinion to counterbalance the tilting action of said tanks.
5. 20. In a displacement pump, a pivotally mounted tank, and liquid inlet means for said tank arranged coaxially with the pivotal axis thereof.
10. 21. In a displacement pump, a plurality of pivotally mounted tanks, and liquid inlet and discharge means for said tanks arranged coaxially with the pivotal axis thereof.
15. 22. In a displacement pump, a pivoted tank, substantially rigid liquid inlet and discharge pipes leading to and from said tank and movable therewith, and stationary means having operative fluid connection with said pipes.
20. 23. In a displacement pump, a pivoted tank, substantially rigid liquid inlet and discharge pipes leading to and from said tank and movable therewith, and stationary means having a fluid and swivel connection with said pipes coaxial to the axis of the tank pivot.
25. 24. In a displacement pump, a fluid container, pressure fluid means for pumping fluid therefrom, means for controlling said latter means comprising a valve, an oscillating weighted arm adapted to control said valve, and cushioning means for said valve.
30. 25. In a pump, a plurality of pivotally mounted tanks, means for admitting pumping medium thereto including a plurality of passages and a ported slide valve adapted to interconnect said passages, and means for controlling said valve by movement of said tanks.
35. 26. In a pump, a plurality of pivotally mounted tanks, means for admitting pumping medium thereto including a plurality of passages and a resiliently positioned ported slide valve controlling said passages, and means for controlling said valve by movement of said tanks.
40. 27. In a displacement pump, a base frame having upstanding members and a transverse shaft, an elongated support pivotally mounted on said shaft, a plurality of tanks carried by said support, counterbalancing means operating with said support, inlet and discharge means for said tanks arranged coaxial with the pivotal axis thereof, and means controlled by the movement of said tank about said pivot for supplying pumping fluid alternatively to said tanks.
45. 28. In a displacement pump, a plurality of pivotally mounted tanks, and a liquid inlet and discharge means for said tanks arranged coaxial with the pivotal axis thereof including a plurality of swivel joints.
50. 29. In a pump, a fluid container, fluid pressure means for pumping fluid therefrom, means for controlling said latter means comprising a valve, an oscillatory weighted arm operatively controlling said valve, and means for causing oscillatory movement of said arm to vary the resisting force thereof from a minimum to a maximum, said valve adapted to be actuated after said force reaches its maximum.
55. 30. In a displacement pump, a plurality of pivotally mounted pumping tanks, means for alternately filling and discharging said tanks comprising control mechanism controlled by the weight of a liquid admitted to said tanks, and means including a single weighted arm to prevent operation of said control mechanism until one of said tanks is filled.
60. 31. In a displacement pump, a plurality of pivotally mounted pumping tanks, means for alternately filling and discharging said tanks, and control mechanism therefor controlled by the tilting action of said tanks including a single swinging weighted arm.
65. 32. In a displacement pump, a plurality of pivotally mounted pumping tanks, means for alternately filling and discharging said tanks, and control mechanism therefor controlled by the tilting action of said tanks including a swinging weighted arm movable with all movements of said tanks.
70. 33. In a displacement pump, a pivotally mounted tank including a transverse shaft about which the tank pivots, and liquid inlet and discharge means for said tank arranged coaxially with said shaft.
75. 34. In a displacement pump, a plurality of movable tanks, means whereby liquid may be supplied to said tanks in alternation, and means whereby pressure fluid is admitted to said tanks to discharge said liquid therein comprising means controlled by the movement of said tanks operative to interconnect the latter prior to the connection of the tank to which pressure has been supplied with a discharge line.
80. 35. In a displacement pump, a plurality of tanks, means for supplying liquid to said tanks in alternation, and tank discharging means, including liquid controlled means, for admitting pressure fluid to each tank to discharge the liquid therein, said tank discharging means operating to interconnect said tanks prior to the connection of the tank to which pressure has been supplied with the discharge line.
85. 36. In a displacement pump, a plurality of tanks, means for supplying liquid to said tanks in alternation, and tank discharging means, including valve mechanism having a lost motion connection, for admitting pressure fluid to each tank to discharge the liquid therein, said tank discharging means operating to interconnect said tanks prior to the connection of the tank to which pressure has been supplied with the discharge line.
90. 37. In a displacement tank, a plurality

of tanks, means for supplying liquid to said tanks in alternation, and tank discharging means, including valve mechanism having actuating means therefor and fluid controlling means for said actuating means, for admitting pressure fluid to each tank to discharge the liquid therein, said controlling

means operating to interconnect said tanks prior to the connection of the tank to which pressure has been supplied with the discharge line. ¹⁰

In testimony whereof I affix my signature.

HALBERT B. HALVORSEN.

CERTIFICATE OF CORRECTION.

Patent No. 1,600,504.

Granted September 21, 1926, to

HALBERT B. HALVORSEN.

It is hereby certified that error appears in the printed specification of the above numbered patent requiring correction as follows: Page 2, line 104, claim 1, strike out the word "tiltable" and insert the same before the word fluid in the same line; and that the said Letters Patent should be read with this correction therein that the same may conform to the record of the case in the Patent Office.

Signed and sealed this 17th day of March, A. D. 1931.

M. J. Moore,
Acting Commissioner of Patents.
